SELF-CLOSING TUBE

Roger S. Manzardo, Berne, Switzerland

Application May 5, 1932, Serial No. 609,430
In Switzerland October 9, 1931

4 Claims. (Cl. 221—60)

This invention relates to a self-closing tube, by means of which the disadvantages of the packing tubes generally in use at the present time are overcome, namely the possibility of displacing, 5 losing or forgetting to close the cap after each use of the tube. As is known, the contents of the tube dry, if the cap is not properly closed and it is further subjected to the action of air and dust.

10 The present invention relates to a self-closing tube, in which the delivery end consists of a closing device made of metal or some other suitable material. The novelty consists in that, on pressure being exerted with the fingers on the wall 15 of the tube in closed condition, discharge apertures situated at a distance apart are brought into communicating position and in this position constitute the aperture for discharging the contents of the tube until the pressure of the fingers 20 is removed from the wall of the tube.

Three embodiments of the invention are illustrated by way of example in the accompanying drawing in which:—

Fig. 1 shows one form of construction of the 25 closure in longitudinal section.

Fig. 2 is a vertical cross section of Fig. 1.

Fig. 3 is a longitudinal section of a modified form of construction of a closure by means of a cap fitted on the end of the tube.

30 Fig. 4 is a top plan view of Fig. 3.

Fig. 5 is a longitudinal section of a third form of construction.

The automatically closing device, fitted on the neck or some other portion of the tube T and 35 made of metal or other suitable material, consists according to the form of construction illustrated in Figs. 1 and 2 of a cylindrical valve piston 1, which is air-tightly enclosed axially shiftable in a valve casing 2 and guided by means of 40 a guide 3 and guide groove 4 in such a manner that the valve piston 1 cannot turn. This valve piston is bevelled towards a passage 5 of the tube on the pressure side 6. A channel 7 extends from this pressure side to the outer wall of the piston 45 and is situated at a distance from a discharge aperture 8 in the valve casing 2. A permanently tensioned pressure spring 9 acts on the other end of the valve piston 1. This spring bears at one end against the closing cap 10 of the casing 2 and at the other end engages in a recess in the piston 1. The strength of the spring is adapted to 50 the consistency of the contents of the tube. The bevelled face or pressure surface 6 and the casing wall opposite same form a wedge-shaped space 55 11 between them.

When pressure is exerted with the fingers on the wall of the tube T, the yielding mass of the tube contents forces its way through the passage 5 into the wedge-shaped space 11 and into the channel 7. The pressure in the mass overcomes 60 the action of the spring and pushes the valve piston to the left, until the channel 7 communicates with the discharge aperture 8. In this position the contents of the tube pass out freely, as long as the finger pressure on the tube wall is 65 maintained. When the channel 7 registers with the discharge aperture 8, the recessed end of the piston bears against the wall of the closing cap 10. When the finger pressure is removed from the tube wall, the pressure of the expanding spiral 70 spring causes the valve piston 1 to return into its initial hermetically closing position of rest, as illustrated in the drawing.

Whereas according to the first form of construction illustrated in Figs. 1 and 2 the valve 75 casing is made in one piece with the tube T so that these parts are inseparable, the second form of construction illustrated in Figs. 3 and 4 is similar to the first form of construction as regards the automatic closing device, but separate and 80 adapted to be screwed onto existing tubes. For this purpose the valve casing 2 has a screw threaded socket 12 at its lower end. The closing head 13 can be screwed on the tube T, after the tube cap has been removed, and it can remain 85 thereon until the tube is empty, when it is fitted to a fresh tube.

The third modification, illustrated in Fig. 5, is a simplified construction, in which the piston 1 is not provided with a passage aperture as in 90 the other constructions, but is solid. On pressure being exerted with the fingers on the wall of the tube, the piston shifts against the action of the spring 9. Thus, the internal space 11 communicating with the passage aperture 5 is enlarged until the piston 1 liberates more or less 95 the passage aperture 8 or establishes intercommunication between the two passage apertures 5 and 8 for the purpose of forcing the contents out of the tube as long as the finger pressure is 100 maintained.

A spiral movement can be imparted by a suitable guide to the piston during its longitudinal movement, so that in this manner the passage apertures are brought into register. The discharge aperture 8 may be of any desired shape.

I claim:—

1. A self-closing device for tubes, comprising in combination a casing on the mouth of the tube having a considerably narrowed passage com- 110

municating with the interior of the tube and a discharge aperture parallel to the longitudinal axis of the tube, a spring-influenced closing element enclosed in said casing between said passage and said aperture and movable in a different direction to the longitudinal axis of the tube a distance at least equal to the width of said discharge aperture, and said closing element having an opening therein adapted to be brought 10 into registry with the passage and discharge aperture.

2. A self-closing device for tubes, comprising in combination a casing on the mouth of the tube having a narrowed passage aperture communicating with the tube and a discharge aperture parallel to the longitudinal axis of the tube, a piston slidable in said casing at right angles to the longitudinal axis of the tube, and a spring in said casing pressing against and tending to 20 force said piston into closing position, and said piston having an opening therein adapted to be brought into registry with the casing passage and discharge aperture.

3. A self-closing device for tubes, comprising in combination a casing on the mouth of the tube having a passage communicating with the interior of the tube and a discharge aperture parallel to the longitudinal axis of the tube, a 30

piston shiftable in said casing at right angles to the longitudinal axis of the tube, one end of said piston having a face bevelled towards said passage so that said passage is always open, the other end of said piston having a recess, and a spring in said casing engaging in said recess adapted to press said piston into closing position, and said piston having an opening therein adapted to be brought into registry with the casing passage and discharge aperture.

4. A self-closing device for tubes, comprising in combination a casing on the mouth of the tube having a passage communicating with the interior of the tube and a discharge aperture parallel to the longitudinal axis of the tube, a spring-influenced piston shiftable in said casing at right angles to the longitudinal axis of the tube, and having at one end a face bevelled towards said passage and a channel extending from said bevelled face to the side remote from said passage, and a spring pressing against the other end of said piston, said piston adapted to be shifted to bring said channel into register with said discharge aperture when pressure is exerted on the tube, and to be returned into closing position by said spring when the pressure is removed from the tube.
